(57) **CLAIM**

The ornamental design for a surface configuration of an engine cover for a vehicle, as shown and described.

DESCRIPTION

FIG. 1 is a perspective view of a surface configuration of an engine cover for a vehicle according to my novel design; FIG. 2 is a rear perspective view of the surface configuration of an engine cover for a vehicle according to my novel design; and,

FIG. 3 is a top view of the surface configuration of an engine cover for a vehicle according to my novel design.

The broken lines are for illustrative purposes only and form no part of the claimed design.
